METAL ROOFING STRUCTURE

Elmer C. Werner, Delphos, Ohio, assignor to
 The New Delphos Manufacturing Company,
 Delphos, Ohio, a corporation of Ohio

Application February 13, 1941, Serial No. 378,787

3 Claims. (Cl. 108—18)

This invention relates to metal roofing sheets, and particularly to the joint structure effected by the lapping side edges of the sheets when applied to a roof.

In roofing joints of this character, it is desirable to provide a channel of considerable depth between the lapping portions of two sheets, which channel is not only for the purpose of drainage, to carry off water which may blow into or enter the channel by capillary action from a side of the joint, but also to provide a free air space of considerable capacity within the joint. It is also found that for efficient operation as a weatherproof joint and for strength, the upper lapping member should have an entrant portion with respect to the channel of the lower member, which portion is of channel form and is spaced from the wall of the lower channel.

The primary object of the invention is the provision of an efficient joint of this type having the characteristics noted and being strong and durable in construction and pleasing in appearance, whereby to enhance the practicability and commercial value thereof.

The invention is fully described in the following specification, and a preferred embodiment thereof illustrated in the accompanying drawing, in which—

Figure 1 is a perspective view of a fragmentary portion of a roof embodying roofing sheets joined in accordance with my invention, and Fig. 2 is a cross-section thereof.

Referring to the drawing, 1 designates the sheathing of a roof and 2 and 3 adjoining roofing sheets of a roofing structure embodying the invention.

Each of these sheets terminates at one side edge (the underlying edge when laid) in a pair of parallel ridges 4 and 5 of the same height and of inverted V-form in cross-section with a V-channel 6 therebetween. The point or bottom of this channel extends to the plane of the sheet and rests on the sheathing 1 as does also the outer legs of each ridge 4, 5. The top of each of these ridges is of truncated form to provide sufficient width to be slightly depressed and form a shallow nailing groove 7 from end to end thereof. The legs of each ridge 4, 5 form oppositely inclined or upwardly converging plane surfaces at approximately the same angle from the plane of the sheet, and the preferable width of each ridge top in practice is approximately five-sixteenths of an inch with a height from the plane of the sheet of approximately five-eighths of an inch, and with the preferable width of the spac-

ing between the ridges at the top approximately seven-eighths of an inch. The legs of the ridge 4 are designated 8 and 9 and those of the ridge 5 are designated 10 and 11.

5 The other side edge of each sheet (the upper or lapping edge when laid) is provided lengthwise thereof with a single ridge 12 having a broad top 13 and having its legs 14 and 15 oppositely inclined. This ridge is adapted to fit closely down over the two ridges 4, 5 of an adjoining sheet with its top resting on the tops of the under ridges and with its legs lying flat against the respective legs 8 and 11 of such ridges, as shown.

10 15 The top 13 adjacent to each side edge, where it rests on the tops of the two underlying ridges 4 and 5, is provided with shallow longitudinally extending grooves 16 which fit into the registering grooves 7 of the underlying ridges and not only facilitate nailing but indicate the line along which nailing should occur.

15 20 The top 13 is also provided lengthwise thereof substantially centrally of its side edges with a depressed portion 17 which enters the top portion 25 of the channel 6 and has its side walls spaced from the side walls of the underlying channel. The depression 17 is preferably of V-form in cross-section with the upper ends of the legs thereof spaced from the upper ends of the legs 30 of the underlying channel 6 and with the apex of the depression spaced a substantial distance from the bottom of said channel, as shown. With this arrangement the depression 17 provides a barrier to prevent any wind, which may pass up 35 between the legs 8 and 14 of the joint, from passing straight across the channel 6 to the top of the farther ridge 5 and carry with it moisture which may then find its way to the roof boards between the legs 11 and 15.

40 45 It is found that if the depression 17 is omitted, there is a tendency for moisture, which may be driven to the top of the ridge 4 by siphonic or capillary action, to follow across the smooth under side of the top 13 to the top of the farther ridge 5 and thence pass down its leg 11 to the under side of the sheet roofing. The purpose of the depression, therefore, is to cause any wind passing to the channel 6 between the members of the joint to be deflected down into the channel, and also to cause any moisture which may traverse the under side of the leg 14 and top 13 of the lapping ridge 12, or any moisture of condensation which might gather on the under side 50 55 of said top 13, to pass down to the lower edge of the depression and then drip into the channel 6

instead of passing to the roof over the ridge 5. This arrangement also provides a drainage trough on the top of the broad lapping ridge 12, imparts strength to said ridge and provides an ample air space within the channel 6 and especially within the walls of the channels 6 and 7, all of which features are desirable in practice.

It will be understood that the ends of the channels 6 and 16 are open for drainage purposes.

Having thus described my invention, what I claim as new, and desire to secure by United States Letters Patent, is:

1. A lap joint for roofing sheets comprising two metal sheets overlapping at their marginal side edge portions, the lapped portion of the under sheet including two parallel ridges of inverted V-form forming a V channel therebetween the same in depth as the ridges and the lapping portion of the upper sheet having a single ridge for fitting down over said under ridges with its legs 20 lying flat against the respective outer legs of the under ridges and with its top bridging said channel and formed centrally of its edges with a longitudinally extending depression forming a trough and extending down into the upper portion of said 25 lower channel in substantially parallel spaced relation to the walls and bottom thereof.

2. A lap joint for roofing sheets comprising sheets adapted to occupy overlapping relation along their meeting edges, the under of said edges having therein a pair of parallel ridges with inclined legs and forming a V channel therebetween with its apex extending to the plane of the sheet, and the other edge having therein a single ridge adapted to fit over the two ridges of 30 the under edge with its legs oppositely inclined and seating flat against the outer legs of the

5 under ridges and having its top resting at its respective side edges on the tops of said under ridges and formed centrally of said under ridges and in spaced relation thereto with a longitudinally extending V depression, the walls and bottom of which are spaced from the walls and bottom, respectively, of said under channel to form a drainage trough in said channel and also a continuous free air space to the top of each leg of the channel.

3. A lap joint for roofing sheets comprising sheets adapted to occupy overlapping relation along their meeting edges, one of said edges having therein a pair of parallel ridges of inverted 15 V-form in cross-section with their tops truncated and longitudinally depressed and with the channel between the ridges of V-form and extending at its bottom to the plane of the sheet, and the other edge having therein a single broad 20 ridge with oppositely inclined legs fitting closely against the outer inclined legs of the under ridges and with its top bridging the space between the two under ridges and having substantially flat 25 portions extending inwardly from each leg to a point in inwardly spaced relation to the respective inner legs of the under ridges and provided with shallow longitudinally extending 30 grooves for nesting in the top grooves of the under ridges, said flat portions having a connecting portion of V-form extending down into said channel with its walls and bottom in substantially parallel 35 spaced relation to the walls and bottom of the channel to form a continuous free air space in the channel from the bottom to the upper ends of its legs.

ELMER C. WERNER.
